(57) **CLAIM**

The ornamental design for a cartridge as shown and described.

DESCRIPTION

FIG. 1 is a first side view of a cartridge;

FIG. 2 is a second side view of the cartridge;

FIG. 3 is a top view of the cartridge;

FIG. 4 is a bottom view of the cartridge;

FIG. 5 is a rear top perspective view of the cartridge;

FIG. 6 is a front bottom perspective view of the cartridge;

FIG. 7 is a front side view of the cartridge; and,

FIG. 8 is a rear side view of the cartridge.

The broken lines, the areas within them, and the unshaded areas bounded by both broken lines and solid lines depict portions of the cartridge that form no part of the claimed design.
